G. CLAUSING

LAST

Filed April 28, 1924

Inventor
GEORGE CLAUSING,
By *Douglas Bulman*
Attorneys

UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

Application filed April 28, 1924. Serial No. 709,476.

To all whom it may concern:

Be it known that I, GEORGE CLAUSING, a citizen of the United States, residing at Portsmouth, in the county of Scioto and State of Ohio, have invented certain new and useful Improvements in Lasts, of which the following is a specification, reference being had therein to the accompanying drawing.

19 My invention relates to lasts and particularly to collapsible lasts.

The object of my invention is to provide a collapsible last which will be so arranged that its movement from one position to the other will be resisted yieldingly. It is a further object of my invention to provide a yielding means and a link in connection with last halves of compressible material, said yielding means being located below the center of movement about which said last halves move.

Referring to the drawings:

Figure 1 is a section through the last in expanded position.

25 Figure 2 is a similar view showing the last parts in collapsed position.

Figure 3 is a plan view of the connecting mechanism connecting the last halves to one another.

30 Referring to the drawings in detail:

1 is the toe part of the last having a cutaway portion 2 to receive the connecting parts. The toe part of the last is provided with a substantially vertical upper rear face 3, the lower end of which terminates in a transversely disposed, semicircular depression 4, the lower end of which is converted into a substantially vertical face 5. The rear or heel part of the last 6 has a

40 corresponding lower vertical forward face 7, a projecting semicircular shoulder 8, and a rearwardly and upwardly extending front face 9. This arrangement permits of the collapsing of the last halves. The semicircular projection 8 describes an arc of a circle greater than 180 degrees according to the preferable method of my construction.

45 10 designates substantially the center about which the last parts move. A pin 11 is transversely mounted in the toe part of the last and the pin 12 is similarly mounted in the heel part of the last. Such pins transverse the cutaway portions 2 and 55 13 in the toe and heel portions of the last,

located in such cutaway portions is an arch-shaped link 14, the extreme ends of which are mounted upon the pins 11 and 12 and the lower ends of which, below the points of connection on the pins 11 and 12 terminate in the hooks 15 and 16 on which are mounted the helical spring 17 which is adapted to resist the movement of the last parts from one position to the other.

It will be noted that the distance between the centers of the pins 11 and 12 will vary as these parts are moved to the respective positions. The spring resists this movement and the compressible character of the material in the lasts permits of some accommodation of this movement over the dead center 10.

It will be understood that I desire to comprehend within my invention such modifications as may be necessary to adapt it to varying conditions.

Having thus fully described my invention, what I claim as new and desire to secure by Letters Patent, is:

1. In a last, a toe part and a heel part adapted to rock about a common center, an extensible link joining said last parts and a yielding means connected to the ends of said link for resisting the movements of its ends and the movement of the last parts.

2. In a last, a toe part, a heel part, a transverse, semicircular projecting shoulder on one part and a corresponding concavity on the other part for receiving said shoulder, a link connecting said parts, either end of which is mounted on a transverse pin in the respective last parts, transverse pins, and a yielding means connected to free ends of said link.

3. In a last, a toe part, a heel part, a transverse, semicircular projecting shoulder on one part and a corresponding concavity on the other part for receiving said shoulder, a link connecting said parts, either end of which is mounted on a transverse pin in the respective last parts, transverse pins, and a yielding means connected to free ends of said link, said yielding means being located below said pins.

4. In a last, a toe part, a heel part, a transverse, semicircular projecting shoulder on one part and a corresponding concavity on the other part for receiving said shoulder, a link connecting said parts, either end of which is mounted on a transverse pin in the

respective last parts, transverse pins, and a yielding means connected to free ends of said link, said pins being located in such position that a line drawn through their centers will pass over the center of movement of the last parts when they are moved from one position to the other.

5. In a last, a toe part, a heel part, a transverse, semicircular projecting shoulder on one part and a corresponding concavity on the other part for receiving said shoulder, a link connecting said parts, either end of which is mounted on a transverse pin in the respective last parts, transverse pins, and a yielding means connected to free ends of said link, said pins being located in such position that a line drawn through their centers will pass over the center of movement of the last parts when they are moved from one position to the other, said last parts being composed of compressible material.

6. In a last, a toe part, a heel part, a transverse, semicircular projecting shoulder on one part and a corresponding concavity on the other part for receiving said shoulder, a link connecting said parts, either end of which is mounted on a transverse pin in the respective last parts, transverse pins, and a yielding means connected to free ends of said link, said pins being located in such position that a line drawn through their centers will pass over the center of movement of the last parts when they are moved from one position to the other, said last parts being composed of compressible material, and yielding means being located to one side of the line joining the centers of the pins.

7. In a last, a toe part, a heel part, means on said parts whereby they will pivot on each other, will be permitted to collapse, but will be limited in their movement in either collapsed or expanded position, said parts moving about a predetermined center, an arch-shaped link mounted on transverse pins in the respective last parts, transverse pins, laterally projecting ends on said links for carrying a spring, and a spring mounted on said link ends.

8. In a last, a toe part, a heel part, means on said parts whereby they will pivot on each other, will be permitted to collapse, but will be limited in their movement in either collapsed or expanded position, said parts moving about a predetermined center, an arch-shaped link mounted on transverse pins in the respective last parts, transverse pins, laterally projecting ends on said links for carrying a spring, and a spring mounted on said link ends, said last parts being composed of compressible material.

9. In a last, a toe part, a heel part, means on said parts whereby they will pivot on each other, will be permitted to collapse, but will be limited in their movement in either collapsed or expanded position, said parts moving about a predetermined center, an arch-shaped link mounted on transverse pins in the respective last parts, transverse pins, laterally projecting ends on said links for carrying a spring, and a spring mounted on said link ends, said last parts being composed of compressible material, and said pins being located so that a line drawn between their centers will be below said central pivotal point when the last is expanded, and above said point when the last is collapsed.

10. In a last, a toe part, a heel part, means on said parts whereby they will pivot on each other, will be permitted to collapse, but will be limited in their movement in either collapsed or expanded position, said parts moving about a predetermined center, an arch-shaped link mounted on transverse pins in the respective last parts, transverse pins, laterally projecting ends on said links for carrying a spring, and a spring mounted on said link ends, said last parts being composed of compressible material, and said pins being located so that a line drawn between their centers will be below said central pivotal point when the last is expanded, and above said point when the last is collapsed, and said spring mounted on the lateral projections located below said line and always below said pivotal point.

In testimony whereof, I affix my signature.

GEORGE CLAUSING.
